Primary Examiner — Wendy L Arminio

Assistant Examiner — Maheen Khurshid

(57) **CLAIM**

The ornamental design for a combined sauna and spa, as shown and described.

DESCRIPTION

FIG. 1 is a front perspective view of a combined sauna and spa showing my new design;

FIG. 2 is a front perspective view of FIG. 1 shown in an alternate configuration in which the sauna room door features are open;

FIG. 3 is another front perspective view of FIG. 1 shown in a state of use;

FIG. 4 is a front perspective view of FIG. 2 shown in another alternate configuration in which the removable sofa bed features have been removed;

FIG. 5 is a front perspective view of FIG. 4 shown in another alternate configuration and state of use in which the sauna room door features are closed;

FIG. 6 is a front perspective view of FIG. 5 shown in another alternate configuration and state of use in which the TV feature has been moved down to a lowered position;

FIG. 7 is another front perspective view of FIG. 4 shown in another alternate configuration in which the lower bench feature inside of the sauna room feature has been folded down;

FIG. 8 is a front perspective view of FIG. 7 shown in another alternate configuration and state of use in which the sauna room door features are closed;

FIG. 9 is a front elevational view of FIG. 1 shown in an alternate configuration in which the sauna room door features are closed;

FIG. 10 is a left side elevational view of FIG. 1;

FIG. 11 is a left side perspective view of FIG. 1;

FIG. 12 is a rear elevational view of FIG. 1;

FIG. 13 is a right side elevational view of FIG. 1; and,

FIG. 14 is a top plan view of FIG. 1.

The broken lines illustrating the human users, treadmill, and exercise bicycle depict environment and form no part of the claimed design. All other broken lines show portions of the combined sauna and spa that form no part of the claimed design.

1 Claim, 14 Drawing Sheets
